CIGARETTE VENDING MACHINE

Walter L. Koch, Wheaton, Ill., assignor to Automatic Canteen Company of America, Chicago, Ill., a corporation of Delaware

Filed Nov. 9, 1961, Ser. No. 67,453

Term of patent 14 years

(Cl. D52—3)

FIGURE 1 is a perspective view of a cigarette vending machine taken from the front and one side thereof, showing my new design;

FIGURE 2 is a side elevational view thereof; and

FIGURE 3 is a partial section taken along the line 3—3 of FIGURE 1.

The undisclosed side of said cigarette vending machine is substantially the same in appearance as the side shown; the rear is substantially flat and plain.

The dominant features of my design reside in the portions shown in full lines, said portions being characterized by the discharge panel located on the lower front of the vending machine as shown.

I claim:

The ornamental design for a cigarette vending machine, as shown and described.
